PUMP CASING

Peter C. Renzo, Paramus, N. J., assignor to Gier-Bath
Gear and Pump Co., Inc., North Bergen, N. J., a
corporation of New Jersey

Application July 16, 1953, Serial No. 26,002

Term of patent 14 years

(Cl. D65—1)

FIG. 1

FIG. 2

FIG. 3

FIG. 4

To all whom it may concern:

Be it known that I, Peter C. Renzo, a citizen of the United States, residing at Paramus, in the county of Bergen and State of New Jersey, have invented a new, original, and ornamental Design for Pump Casings, of which the following is a specification, reference being had to the accompanying drawing, forming part thereof.

Fig. 1 is a top plan view of a pump casing showing my new design;

Fig. 2 is a side elevation thereof which is the same on the opposite side;

Fig. 3 is a front elevation thereof; and
Fig. 4 is a rear elevation thereof.

I claim:

The ornamental design for a pump casing, as shown and described.

UNITED STATES PATENT OFFICE
CERTIFICATE OF CORRECTION

Design No. 173,856

January 11, 1955

Peter C. Renzo

It is hereby certified that error appears in the above numbered patent requiring correction and that the said Letters Patent should read as corrected below.

The name of the assignee in the above numbered patent was erroneously printed as "Gier-Bath Gear and Pump Co., Inc.", whereas the name should have been printed as --Sier-Bath Gear and Pump Co., Inc.--.

Signed and sealed this 1st day of March, 1955.
